UNITED STATES PATENT OFFICE.

HUGO A. HEIZMANN, OF BOSTON, MASSACHUSETTS.

DESIGN FOR A TRAY OR SIMILAR ARTICLE.

58,186.

Specification for Design.

Patented June 21, 1921.

Application filed November 22, 1920. Serial No. 425,924. Term of patent 3½ years.

To all whom it may concern:

Be it known that I, HUGO A. HEIZMANN, a citizen of the United States of America, residing at Boston, in the county of Suffolk and Commonwealth of Massachusetts, have invented a new, original, and ornamental Design for a Tray or Similar Article, of which the following is a specification, reference being had to the accompanying drawing, forming a part thereof.

In said drawing, Figure 1 is a plan view of a tray showing my new design; and

Fig. 2 is a section on the line 2—2 of Fig. 1.

I claim—

The ornamental design for a tray or similar article, substantially as shown.

Signed by me at Boston, county of Suffolk, Commonwealth of Massachusetts, this 19 day of November, 1920.

HUGO A. HEIZMANN.
